SHEET SEVERING EQUIPMENT

Rudolph O. Smith, Pennington, and Merlin H. Becher,
Hopewell, N. J.

Application May 25, 1954, Serial No. 432,072

2 Claims. (Cl. 164—84.5)

This invention relates to equipment for severing lengths of paper or other sheet material from a roll or supply thereof, and is directed particularly to constructions in which the material is severed primarily by tensioning or rupturing action as distinguished from the usual shearing action of equipment of the prior art.

There are many situations in which sheets or lengths of paper are required for covering, separating or wrapping articles. In some instances the sizes of the sheets required vary considerably in successive uses whereas other applications call for sheets of uniform size. In any case the sheets must be severed from a roll or supply of paper either before or during the actual use thereof.

The equipment heretofore employed for this purpose has included a movable shear or knife edge which cooperates with another shear or knife which may be either movable or stationary. Such shearing elements must of necessity be made of high grade steel and require frequent sharpening. Moreover, they frequently have to be adjusted in position to insure proper cutting engagement of the relatively moving parts.

In accordance with the present invention accurate adjustment of the elements is made unnecessary and knife edges and similar means can be eliminated altogether. The sheet material to be severed is instead gripped by two pairs of relatively movable clamping members which serve to rupture the paper or pull it apart by a tensioning action applied along a predetermined line to sever the desired length of material from the roll or supply. If desired a straight edge or knife can be used in combination with one or more elements of the present invention but such additions are not necessary for most purposes.

One of the objects of the present invention is to provide a novel type of equipment for severing sheet material from a roll or supply wherein the use of cutting blades are unnecessary.

Another object of the invention is to provide sheet severing equipment wherein the sheet material is severed by a tensioning action.

A further object of the invention is to provide novel means for controlling the operation of sheet severing equipment.

These and other objects and features of the present invention will appear from the following description thereof in which reference is made to the figures of the accompanying drawings:

In the drawings:

Fig. 1 is a side elevation of a typical form of sheet severing equipment embodying the present invention;

Fig. 2 is a front elevation of the construction shown in Fig. 1;

Figs. 3 and 4 are vertical sectional views through the clamping means embodied in the construction of Figs. 1 and 2 with the elements in different operative positions; and

Fig. 5 is a detailed view illustrating the drive means for the paper feeding rolls of Fig. 1.

That form of the invention chosen for purposes of illus-

2

tration is particularly adapted for use in severing sheets of paper from a roll for use as separators placed between coil springs to the compressing and baling of such springs for storage and shipment. As shown the springs 2 are brought to the paper severing equipment by a conveyor 4 so as to be positioned in front of the vertical stand 6 on which the paper severing equipment is mounted. A web of paper 8 is drawn from the roll 10 and passes over the roll 12 to the rubber coated paper feeding rolls 14. From the feeding rolls the paper passes between the upper and lower elements of the sheet severing means indicated generally at 16 and thence passes downward over the spaced sheet supporting forks 18.

The equipment preferably includes control means whereby the feed rolls 14 will be stopped and the sheet to be severed will be held stationary whenever a predetermined length of paper has been fed through the device. In the construction shown the control means includes an electrical circuit (not shown) under the control of a photoelectric cell 20 and source of light 22 which are mounted on a carriage 24 movable along the track 26 to any desired position corresponding to the length of the sheet to be severed. The leading edge of a sheet moving over the supporting forks 18 will interrupt the beam of light from source 22 and thereby actuate photo-electric cell 20 in a manner which serves to stop the motor 28 by which the feed rolls 14 are driven. The position of the carriage 24 on track 26 will therefore determine the length of the sheet fed out onto the forks 18. When the sheet is thereafter severed from the roll and removed from forks 18 the beam of light from source 22 will again fall on the photoelectric cell 20 which in turn will be actuated in a manner which serves to start motor 28 and cause another sheet to be fed out onto the forks 18. By changing the position of the carriage on track 26 the length of the sheet to be severed can be varied at the will of the operator.

A preferred form of sheet severing means 16 is illustrated in detail in Figs. 3 and 4 and includes a lower stationary base 32 together with an upper movable head 34. The head 34 is mounted for vertical movement toward and away from the base and is guided during such movement by the guide posts 36. The base 32 is provided with a stationary clamping member 38 adjacent to which is located a movable clamping member 40. The member 40 is urged upward by a spring 42 and is guided in its movement by the rod 44 having stop nuts 46 secured to the lower end thereof and engageable with the stationary block 48 mounted on the base 32. The upper surface of the movable clamping member 40 is provided with a friction facing 50 formed of leather, rubber or the like for engaging and gripping the web of paper 8 passing over its surface.

The movable head 34 of sheet severing device is provided with similar clamping means arranged in the reversed positions so that the stationary member 52 will engage the spring pressed clamping element 40 mounted on the base. In a similar way the spring pressed clamping member 54 on the head 34 is positioned to engage and cooperate with the stationary clamping member 38 on the base.

The head 34 and the upper clamping members 52 and 54 are movable vertically by suitable means such as the pull rod 56 provided with an eccentric 58 at its lower end engageable by the eccentric cam 60 on cam shaft 62. The cam shaft is driven by a sprocket 64 and chain 66 from the motor 68. The cam shaft is controlled by clutch means 70 designed to be actuated by a trip 72 whereby the severing mechanism 16 will be caused to perform a single operation and thereafter remain stationary until again actuated by operation of the trip. The trip is actuated by an operator standing in front of the con-

veyor 4 through movement of the pedal 74 and trip actuating cable 76.

With the construction described the desired length of paper is fed through the sheet severing device by feed rolls 14. Thereafter, when the sheet is to be severed from the roll the operator depresses the pedal 74 whereupon the trip 72 is actuated and the cam shaft 62 is caused to make a single revolution whereby the eccentric 58 causes the pull rod 56 to be moved downward so that the head 34 of the severing mechanism is lowered. As the head moves downward the gripping elements 52 and 54 move from the idle position of Fig. 3 to the severing position of Fig. 4. The stationary gripping element 52 on the head then is moved downward into contact with the web of paper 8 and presses the paper against the spring urged movable gripping element 40 mounted on the base 32. At the same time the spring urged gripping element 54 on the head is placed against the web of paper 8 so as to urge it against the stationary gripping element 38 on the base. As the head continues to move downward the springs 42 associate with the movable gripping elements 40 and 54 are compressed and the adjacent portions of the sheet of paper are thereby firmly gripped between the clamping elements. When the lower edge of the stationary gripping element 52 moves past the upper edge of stationary gripping element 38 the paper gripped and held by the pairs of elements is placed under tension sufficient to cause it to be ruptured. The pair of gripping elements 38 and 54 are preferably located close to the pair of gripping elements 40 and 52 so that the rupturing occurs along a substantially straight line. If desired, the adjacent corners 76 and 78 of the stationary gripping elements may be right angularly formed so as to present abrupt straight edges insuring a clean sharp severance of the paper as it is placed under tension by operation of the severing equipment. However, the use of a knife edge or sharp steel blade in forming the corners 76 and 78 is not necessary in view of the fact that the severance of the web is actually effected by tensioning of the web rather than by conventional shearing operations.

After the paper thus fed out has been severed from the roll the paper supporting forks are depressed by operation of the pedal 80 and the cable 82 against the tension of the spring 84. The latter spring normally holds the forks 13 in the raised full line position illustrated in Fig. 1 but when pedal 80 is depressed the forks are lowered to the dotted line position of Fig. 1 and the severed length of paper shown at 86 is delivered to the operator. On release of the pedal 80 the forks return to the full line position shown whereby another length of paper fed out onto the forks is held in position to cause the light beam to be broken when the desired length has been drawn from the roll.

When springs of a different width are supplied to the operator, he merely moves the photoelectric cell assembly along the rail 26 to a new position corresponding to the desired width of the sheet to be used whereupon the operations are repeated in an identical manner. However, if a continuous or extended length of paper is re-

quired for any reason the pedal 80 may be held depressed so that the sheet being fed will not pass between the photoelectric cell 20 and the light source 22. The feed rolls 14 will, therefore, continue to advance the sheet material as long as desired and until the required length has been drawn off the roll or the roll is emptied.

While the invention has been described with particular reference to equipment for use in severing lengths of paper to be used as separators between coil springs, it will be apparent that the equipment may be used for innumerable other purposes as when wrapping laundry or other articles or when the sheets are to be used for any desired purpose. Furthermore, the equipment may, of course, be used for severing lengths of material other than paper such as metal foil, transparent sheet material or fabrics.

It will also be apparent that other types of control means may be used in place of the photoelectric cell assembly and any suitable form of power operated means may be used for actuating the sheet severing device. In view thereof it should be understood that the particular embodiment of the invention chosen for purposes of illustration in the drawings is intended to be typical and illustrative only and is not intended to limit the scope of the invention.

We claim:

1. Sheet severing means comprising sheet feeding rolls, a motor for actuating said rolls, movable sheet supporting means over which a sheet from said rolls is passed, control means responsive to the position of the leading edge of said sheet when said sheet supporting means is in a sheet supporting position for controlling operation of said motor, sheet severing means located between said feed rolls and control means, and means for actuating said sheet severing means, said sheet supporting means being movable to a sheet discharging position to render said control means inoperative.

2. A web handling device comprising web feeding rolls, a motor for actuating said rolls, movable web supporting means over which the web from said rolls is passed, control means responsive to the position of the leading edge of said web when said web supporting means is in a web supporting position for controlling operation of said motor, an electrical circuit completed by said control means upon movement of the leading edge of said web to a predetermined position, said web supporting means being movable to a web discharging position to render said control means inoperative.
